(57) **CLAIM**

The ornamental design for a foot pad for electric vehicle, as shown and described.

DESCRIPTION

FIG. 1 is a top, front perspective view of a first embodiment of the new design for a foot pad for electric vehicle, showing an illustration of use on an electric vehicle;

FIG. 2 is another top, front perspective view thereof, with the exemplary electric vehicle removed for clarity of details;

FIG. 3 is a top, rear perspective view thereof;

FIG. 4 is a left side view thereof;

FIG. 5 is a right side view thereof;

FIG. 6 is a front view thereof;

FIG. 7 is a rear view thereof;

FIG. 8 is a top view thereof;

FIG. 9 is a bottom view thereof;

FIG. 10 is a top, front perspective view of a second embodiment of the new design for a foot pad for electric vehicle, showing an illustration of use on an electric vehicle;

FIG. 11 is another top, front perspective view thereof, with the exemplary electric vehicle removed for clarity of details;

FIG. 12 is a top, rear perspective view thereof;

FIG. 13 is a left side view thereof;

FIG. 14 is a right side view thereof;

FIG. 15 is a front view thereof;

FIG. 16 is a rear view thereof;

FIG. 17 is a top view thereof; and,

FIG. 18 is a bottom view thereof.

The broken lines shown in the drawings illustrate environment and portions of the foot pad for electric vehicle that form no part of the claimed design.

The shading lines shown in the drawings represent the approximate three-dimensional contour of the design, and are not intended to indicate surface decoration.
